RAILWAY-TRAFFIC-CONTROLLING APPARATUS.

1,398,383.

Specification of Letters Patent. Patented Nov. 29, 1921.

Original application filed March 12, 1915, Serial No. 13,853. Renewed as Serial No. 270,749, filed January 11, 1919. Original application divided and this application filed February 15, 1918. Serial No. 217,300.

To all whom it may concern:

Be it known that I, LLOYD V. LEWIS, a citizen of the United States, residing at Edgewood Borough, in the county of Allegheny and State of Pennsylvania, have invented certain new and useful Improvements 5 in Railway-Traffic-Controlling Apparatus, of which the following is a specification.

My invention relates to railway traffic 10 controlling apparatus, and particularly to apparatus for controlling the speed of railway cars or trains.

The present application is a division of my co-pending application filed March 12, 15 1915, Serial No. 13853, for speed controlling apparatus for railway vehicles.

I will describe one form of traffic controlling apparatus embodying my invention, and will then point out the novel features 20 thereof in claims.

In the accompanying drawings, Figure 1 is a diagrammatic view showing one form 25 of trackway apparatus embodying my invention. Fig. 2 is a diagrammatic view showing a train of two vehicles equipped with one form of apparatus adapted to co-operate with the trackway apparatus shown in Fig. 1.

Similar reference characters refer to similar parts in each of the two views.

Referring first to Fig. 1, the reference characters 1, 1 designate the track rails of a railway over which traffic moves in the direction indicated by the arrow, one of 35 which rails is divided by insulated joints 2 to form blocks E, F and G. The same rail is further divided by a joint 2^a within each block to form a main track section and a preliminary track section, which sections 40 are designated by the reference characters M and P together with exponents corresponding to the letters designating the block. For example, block E is provided with a main section M^E and a preliminary section P^E.

Each block is provided with a device which is adapted, when energized, to transmit energy to a car or train. Each of these devices is designated by the reference char-

acter R with an exponent corresponding to 50 the reference character of the block section for which the device is provided. These de-

vices are, as here shown, contact rails which co-act with contact shoes carried by the trains, although I do not wish to limit myself to this particular type of device for transmitting energy to the trains. Each of these contact rails is located opposite the preliminary section for the corresponding block.

The contact rail R^E is provided with an energizing circuit which is controlled by a stick relay C^E and a line relay D^E, this circuit being from secondary a of the adjacent transformer T^E, through wire 4, contact 5 of relay D^E, wire 6, contact 7 of relay C^E, wire 8, to rail R^E. When a train occupies the preliminary section P^E, this circuit is completed through a contact shoe on the train, suitable controlling apparatus on the train, one or 70 more axles on the train, thence through upper rail 1 and wire 9 to secondary a of transformer T^E. Current flowing in this circuit operates the train-carried apparatus to give the proceed or high speed signal 75 aboard the train. If the rail is deenergized, however, the elevation of the shoe by the contact rail causes the train-carried apparatus to give the low speed indication. Relays C^E and D^E are controlled in a manner 80 hereinafter explained. Each contact rail is controlled by the adjacent relays C and D in the same manner as rail R^E.

Each track section is provided with a track circuit comprising, as usual, the track 85 rails of the section, a source of current connected across the rails adjacent the exit end of the section, and a track relay connected across the rails adjacent the entrance end of the section. For example, the source of current for main section M^E is a secondary b of a transformer T^E, and the track relay for this section is designated B^E. Similarly, the source of current for the preliminary section P^E is a secondary c of transformer T^E 90 and the track relay for the same section is designated A^E. The primary winding of each transformer T^E, T^F, etc., is supplied with alternating signaling current from a suitable source which is not shown in the 100 drawing.

Line relay D for each block is controlled by the track relays for the main and the preliminary sections of the block next in ad-

vance. The circuit for relay D^E for section E, for example, is from secondary d of transformer T^E , through wire 10, contact 11 of relay B^E , wire 12, contact 13^a of relay A^E , wire 14, relay D^E , wires 15 and 16, common wire X, and wire 17 to secondary d of transformer T^E . It follows, then, that relay D^E will be open, that is, contact rail R^E will be deenergized, whenever a train occupies any 10 part of block F.

Relay C^E is a stick relay, the pick-up circuit being from secondary d of transformer T^E , through wire 18, contact 19 of relay B^E , wires 20 and 21, relay C^E , wires 16, X and 22 to secondary d of transformer T^E . Relay C^E will be open, therefore, whenever a train occupies the main track section M^E , unless the stick circuit for this relay is closed. This stick circuit is from the secondary d of transformer T^E , through wires 18 and 23, contact 24 of relay C^E , wire 25, contact 13^b of relay A^E , wire 21, relay C^E , wires 16, X and 22 to secondary d of transformer T^E . It follows, then, that when a train enters preliminary section P^E and opens relay A^E , the stick circuit for relay C^E becomes closed provided the main track section M^E is unoccupied, and that consequently relay C^E remains closed until 20 the rear end of the train passes out of preliminary section P^E . In other words if section M^E is unoccupied when a train enters section P^E , stick relay C^E will remain closed as long as any part of the train is in section 25 P^E . Hence, if more than one car of the train is equipped with a contact shoe and controlling apparatus, and if contact rail R^E is energized when the train enters preliminary section P^E , the entrance of the forward 30 part of the train into the main section M^E will not deenergize rail R^E , and so all cars on the train will receive the proceed indication at this rail.

Relays C and D for each block are controlled in the same manner as relays C^E and D^E for block E.

Referring now to Fig. 2, I have here shown a train comprising two cars V and W, each of which is equipped with apparatus adapted to coöperate with the trackway apparatus shown in Fig. 1. Each car carries a contact shoe U which is so located as to make electrical contact with each contact rail R, and each shoe is arranged to be elevated by the contact rail so as to open a normally closed contact 35. Extending throughout the train are two battery wires 30 and 31, which are connected with a battery 32 carried by one of the cars, and a third wire 33 the function of which will appear hereinafter.

Each car is provided with two relays H and K. The two terminals of the winding of relay H are connected with the shoe U 65 and with an axle of the car by wires 43 and

44, so that this relay is energized momentarily each time that the shoe U passes over a contact rail R which is energized. Relay K is normally energized by virtue of a circuit (see car W), which passes from battery wire 30, through wire 34, contact 35, wire 36, front point of contact 37, wire 38, winding of relay K, and wire 39 to battery wire 31. This circuit is opened at contact 35 each time that contact shoe U engages a contact rail R, but if the rail R is energized so that relay H is energized, relay K is held in the energized condition by virtue of a branch circuit which passes from battery wire 30, through wire 40, contact 41 of relay H, wire 42, wire 38, winding of relay K, and wire 39 to battery wire 31. Furthermore, if relay K is already deenergized when shoe U engages contact rail R, this relay will become energized, provided that the contact rail is energized, because of the pick-up circuit closed by the closure of contact 41 of relay H.

I will now assume that relay K of each car is deenergized, and that the shoe U on car W engages an energized contact rail R. The consequent closure of contact 41 of relay H on car W, closes the pick-up circuit for relay K on the same car, so that the latter relay becomes energized. The closure of contact 48 of relay H also closes a pick-up circuit for relay K on car V, this circuit being from battery wire 30, through wire 40 of car W, contact 48 of relay H, wire 45, wire 33 to car V, thence through wire 46, back point of contact 37 of relay K, wire 38, winding of relay K, and wire 39 to battery wire 31. The front and the back contacts of each relay K are so arranged that when the relay becomes energized, the back contact remains closed until after the front contact has become closed. It follows, therefore, that when relay K on car V becomes energized, through the circuit just traced, this relay remains energized, because its stick circuit through contact 35 becomes closed before the pick-up circuit is opened at the back point of contact 37.

Each relay K is provided with a contact 115 47 which may be utilized to control any suitable train governing apparatus in such manner that when this contact is closed the train is permitted to proceed at or below a given high speed, but that when this contact is open, the speed of the train is automatically reduced to at least a given low value unless the speed is already at or below such given value. One form of train governing apparatus which may be controlled by the contact 47 is shown and described in 120 my parent application, Serial No. 270749, which is a renewal of Serial No. 13,853 of which the present application is a division.

It will be seen from the foregoing that when a low speed indication has been given 130

aboard the train and either car of the train encounters an energized contact rail R^E , the proceed or high speed indication received on such car is at once transmitted to the 5 other car, so that the train may resume full speed at once.

Referring again to Fig. 1, the operation of the trackway apparatus shown therein, is as follows:

10 Assuming that blocks E and F are unoccupied, as shown in the drawing, contact rail R^E will be energized, because relays C^E and D^E are both energized. If now a train, moving in the direction indicated by the 15 arrow, enters preliminary track section P^E , it will open track relay A^E , thereby closing the stick circuit for relay C^E , so that contact rail R^E will remain energized as long as any part of such train occupies the preliminary 20 section P^E . Contact rail R^E being energized, the proceed indication will be given aboard the train each time that a car of the train equipped with the train-controlling apparatus passes over this rail. As the train 25 passes into main section M^E , it opens relay B^E , but this has no effect on stick relay C^E until the entire train has passed out of preliminary section P^E , whereupon relay C^E opens, due to the fact that its stick relay becomes 30 opened at contact 13^b of relay A^E .

As the train passes into preliminary section P^F , it opens track relay A^F , which in turn opens the circuit for line relay D^F , so that contact rail R^F continues to be deenergized, even after the rear end of the train 35 passes out of main section M^E . The opening of track relay A^F closes the stick circuit for relay C^F , so that contact rail R^F continues to be energized until the rear end of the 40 train leaves preliminary section P^F . As the train passes into main section M^F , the opening of track relay B^F opens at contact 11 the circuit for line relay D^F , so that this latter relay remains open, that is, contact rail R^F 45 remains deenergized as long as any part of the train occupies main section M^F .

When the rear end of the train passes out of main section M^F , track relay B^F closes, so that relay D^F closes, whereupon contact 50 rail R^F again becomes energized.

I will now assume that block F is occupied at the time that the train enters preliminary section P^E . Relay D^E is then open, so that rail R^E is deenergized. As the first 55 car of the train which is equipped with controlling apparatus passes over this rail, the low speed indication will, of course, be given aboard the train. Relay B^E being closed, however, relay C^E is likewise closed and remains 60 closed, even after the forward part of the train enters section M^E . If now, before the entire train has passed over rail R^E , the vehicle which has been in block F passes out thereof, relay D^E will close, so that rail 65 R^E will become energized. The next car

equipped with controlling apparatus to pass over this rail will then receive the proceed signal indication, which indication will at once be transmitted to every car in the train, so that the train may at once resume full speed. It will be seen, therefore, that when section M^E is unoccupied and block F is occupied, and a train enters section P^E , relay C^E virtually stores an indication of the condition of section M^E , so that should block F 70 subsequently be vacated while the train is partly in section P^E and partly in section M^E , rail R^E will become energized to give the proceed indication aboard the train.

Although I have shown only one form of 80 apparatus embodying my invention, it is understood that various changes and modifications may be made therein within the scope of the appended claims without departing from the spirit and scope of my invention.

Having thus described my invention, what I claim is:

1. In combination, a railway track divided into a plurality of successive blocks each 90 comprising a main section and a preliminary section, a track circuit for each section including a track relay, a line relay for each block controlled by both track relays for the block next in advance, a stick relay for each 95 block having a pick-up circuit controlled by the track relay for the main section of the block and a holding circuit controlled by a back contact of the track relay for the preliminary section of the block, a device for 100 each block for transmitting energy to a train, and means for controlling each said device by the line relay and by the stick relay for the same block.

2. In combination, a railway track divided 105 into a plurality of successive blocks each comprising a main section and a preliminary section, a track circuit for each section including a track relay, a line relay for each block controlled by both track relays for the 110 block next in advance, a stick relay for each block, a pick-up circuit for each stick relay including a front contact of the track relay for the main section of the corresponding block, a holding circuit for each stick relay 115 including a back contact of the track relay for the preliminary section of the corresponding block and a front contact of the stick relay itself, a device for each block for transmitting energy to a train, and means for 120 energizing each said device only when both the stick relay and the line relay for the corresponding block are energized.

3. In combination, a railway track divided into a plurality of successive blocks; 125 means for determining the condition of occupancy of each block; means for each block for storing an indication of said condition from the time a train enters the block until the rear of the train has passed a pre- 130

determined point in the block; means for each block for determining the condition of occupancy of the next block in advance, and a device for each block located at or in the rear of said point for transmitting signals to the train and controlled by said last-mentioned means and by said storing means.

4. In combination, a railway track divided into a plurality of blocks each comprising a main section and a preliminary section, track circuits including track relays for the said sections, a device for each block for transmitting energy to a train, means for controlling each said device by the track relays for the main section of the corresponding block and both sections of the block next in advance, and means for each device controlled by the track relay for the preliminary section of the corresponding block for removing such device from control by the track relay for the main section of the corresponding block while such preliminary section is occupied.

5. In combination, a railway track divided into a plurality of blocks each comprising a main section and a preliminary section, a device for each block for transmitting energy to a train, train-controlled means for each device for deenergizing the device when the main section of the corresponding block or either section of the block next in advance is occupied, and means controlled by a train occupying a preliminary section for removing the corresponding device from control by the presence of a train in the main section of the same block.

6. In combination, a block of railway track comprising a main section and a preliminary section, a track circuit for said main section, a relay normally controlled by said track circuit, an impulse device located in said preliminary section and controlled by said relay, and means controlled by the presence of a train in said preliminary section for keeping said relay ener-

gized regardless of the entrance of a portion of said train into the main section of the block.

7. In combination, a block of railway track comprising a main section and a preliminary section, a track circuit for said main section, a track circuit for said preliminary section, a relay, a main circuit for said relay controlled by the track circuit for the main section, an auxiliary circuit for said relay controlled by the track circuit for the preliminary section and by a front contact of said relay, and an impulse device located in said preliminary section and controlled by said relay.

8. In combination, a block of railway track, a stick relay, a main circuit for said relay, means controlled by a train in said block for opening said main circuit, a stick circuit for said relay, means controlled by a train entering said block for closing said stick circuit before opening said main circuit, and an impulse device located adjacent the entrance end of said block and controlled by said relay, said stick circuit being held closed as long as a train is passing said impulse device.

9. In combination, a block of railway track, a trackway impulse device for said block, a stick relay for controlling said device, a normally closed main circuit and a normally open stick circuit for said relay, means controlled by a train in said block for opening said main circuit, and means controlled by a train entering said block for closing said stick circuit before opening said main circuit and for keeping said stick circuit closed until the train has passed said impulse device.

In testimony whereof I affix my signature in presence of two witnesses.
